HYDRAULIC HAT PRESS

Morris A. Schwartz, Los Angeles, Calif., assignor
of one-half to George Cheroff, Los Angeles,
Calif.

Application February 13, 1931, Serial No. 515,475
Renewed August 21, 1934

22 Claims. (Cl. 223—31)

My invention pertains to a hydraulic hat press in which one element of the press has a mold or form for the hat and another element an inflatable rubber bag which may be pressed into the hat to mold the same and in which the mold and the rubber bag are separable for inserting and removing the hat.

In the above mentioned type of hat press an object and feature of my invention is constructing the mold and the pressure block on two opposed parts of the machine, these opposed parts both having a reciprocating motion in opposite directions whereby these may be engaged or separated. In the engaged position the bag may be inflated for pressing the hat and in the separated position will allow inserting and removing the hat. In this connection a further detailed feature of my invention is constructing the mold carrying and the bag carrying part of the machine to more or less balance each other where, when the reciprocating motion is conveyed to both parts of the machine simultaneously, these operate to form a tight closure between the mold and the peripheral portion of the bag, and after 25 clamping of the mold and the bag the bag may be inflated by a hydraulic medium.

A further detailed feature of my invention in connection with the opposed moving parts of the machine, that is, the part having the mold and the inflatable bag, is an arrangement for operating said devices by a mechanical leverage system, using a series of levers and links for moving one part relative to the other and to effect a toggle-like pressure action when the mold comes in contact with the periphery of the rubber bag.

Another object and feature of my invention is operating the press hydraulically in which one or more cylinders are utilized to effect the approach and the separation of the two parts of the machine, the lower part preferably carrying the mold and the upper part the pressure bag. In this hydraulic arrangement a further feature and object of my invention is the inserting of equal pressures through the bottom to press the mold upwardly and on the upper part to force the bag downwardly to form a tight seal before inflation of the bag.

Another object and feature of my invention is a clamp for interengaging the mold carrying element and the bag carrying element to secure these in a tight relationship prior to the development of the hydraulic pressure of the bag and thereby hold the mold and the bag in contact without relying on the weight of the various parts

of the machine or the mechanical or hydraulic action used to contact the mold and the bag portion of the machine. In this connection another detailed feature of my invention is a mechanically operated type of clamp, said clamp having a split band partly encircling the periphery of the bag carrying structure and the mold carrying structure. 5

In the hydraulic arrangement a further object and feature of my invention is a hydraulically operated clamp which exerts a pull on the split band or releases such band for clamping or unclamping the mold or the bag carrying parts of the machine. 10

My invention is illustrated in the accompanying drawings in which:

Fig. 1 is a front elevation taken in the direction of the arrow 1 of Fig. 2.

Fig. 2 is a plan taken in the direction of the arrow 2 of Fig. 1.

Fig. 3 is a vertical section taken on the line 3—3 of Fig. 1 with the machine in the pressing position.

Fig. 4 is a section similar to Fig. 3 with the machine in the open position.

Fig. 5 is a plan of the split clamp ring.

Fig. 6 is an enlarged section on the line 6—6 of Fig. 5 in the direction of the arrows.

Figs. 7 and 8 are enlarged front elevations of the double lever and link mechanism for loosening and tightening the clamping ring. 30

Fig. 9 is a detail, partial, horizontal section on the line 9—9 of Fig. 1 illustrating part of the frame of the machine.

Fig. 10 is an elevation partly in section of a 35 hydraulically operated type of machine.

Fig. 11 is a detailed section on the line 11—11 of Fig. 10 showing part of the clamp operating device.

Fig. 12 is a partial, vertical section on the line 12—12 of Fig. 11 in the direction of the arrows giving details of the hydraulic clamp.

Fig. 13 is a section similar to Fig. 12.

Figs. 14 and 15 are sectional views of a suitable valve for the hydraulic operation. 45

Referring first to the mechanical construction of my invention of Figs. 1 through 9 I employ a stand 11 having suitable legs. This stand has vertical guide bearings 12 through which extend a pair of side rods 13. These side rods at 50 the bottom are supported by a cross head 14. At the top of the rods there is a substantial bar or beam 15 being adjustably secured on the screw threaded ends of these rods and from this beam there depends a neck structure 16. Connected to 55

the bottom of this neck there is a bag holding structure designated generally at 17. This bag holding structure has a dome 18 with the rubber 19 forming the bag, and a washer 20 secured at the periphery of the bag.

Slidably mounted on the rods 13 there are a pair of guides 21 which have brackets 22 secured thereto. These brackets support the mold structure designated generally at 23. This mold structure has a bottom plate 24 and side walls 25 resting thereon, these walls having openings 26. The mold block 27 has a central downward projection 28 resting on the bottom plate 24. The mold has a lateral flange 29 resting on the upper edge of the side walls 25. The gas jet pipes 30 surround the lower part of the mold and the openings 26 form a supply of air for the gas burners for heating the mold. The rods 13 move up and down, carrying the rubber bag, and the mold and its supporting structures have a vertical motion on the rods, such motion being derived as follows:

A cross shaft 31 is mounted in the frame 11 of the machine and this carries a double lever 32. This double lever has a short single lever 33 connected thereto and a link 34 is swiveled on this lever 33 and to a lever 35 which oscillates on a pivot shaft 36 secured to the legs of the machine. The pivot shaft is oscillated by means of a hand lever 37. A pair of links 38 connect from one end of the double lever 32 to lugs 39 on the cross head 14, which cross head carries the vertical rods 13, and a second pair of links 40 are connected from the opposite end of the double lever 32 to lugs 41 on the bottom plate 24 of the mold carrying structure. Thus, when the lever 39 is oscillated it rocks the double lever 32 through the medium of the link 34 and the action is to shift the links 38 and 40 between the positions illustrated in Figs. 3 and 4 so that in the position of Fig. 3 the cross head is lowered, hence the bag carrying unit is lowered and the mold carrying unit is elevated, and in the arrangement of Fig. 4 the cross head with the bag carrying unit supported on the rods 13 is elevated and the mold carrying unit is lowered. In the position of Fig. 3 the hat may be subjected to the hydraulic pressure and in Fig. 4 the hat may be inserted and removed.

The type of clamp used comprises a clamping ring 42 having two arms 43 connected by a hinge 44. Each of the arms is channel-shaped and has a web 45 with upper and lower flanges 46. Projecting inwardly on the upper flange there are a series of studs 47 (note Figs. 5 and 6). Mounted on the front of the arms there are a pair of lugs 48 to each of which is pivotally connected a curved link 49. These links are attached to a double lever 50, which double lever may oscillate on a pivot pin 51, which pivot pin is attached to the rim 52 of the dome 18 carrying the inflatable bag. The lugs 47 are adapted to bear upon this rim and thus maintain the clamp from slipping downwardly. An operating handle 53 is attached to the double lever and may be utilized to swing this lever to exert a pull or a thrust on the links and thus pull the arms 43 of the clamp into tight clamping engagement or to loosen these arms. The lower flange of the clamp fits over the lateral flange of the hat mold structure 23. Therefore, when the mold and the inflatable bag structure are brought together and clamped a hydraulic pressure may be inserted in the bag without any danger of forcing the bag and the

mold apart and not requiring the weight of the various parts to hold these together.

The dome is provided with the usual connections to a hydraulic supply such as a pipe 54 leading to a source of hydraulic supply, a relief pipe 55, a hydraulic pressure gauge 56, and a petcock 57 for release of the air in the bag.

A pump 58 is provided operated by a pump handle 59 for pumping the hydraulic fluid into the dome to expand the rubber bag.

In the operation of the mechanically operated press illustrated in Figs. 1 to 9 it will be apparent that a considerable pressure may be exerted between the mold and the dome element carrying the bag and that this factor in itself tends to hold the bag firmly in position. In addition to this the clamp when secured to the rim of the dome 18 and to the margin of the mold absolutely prevents separation of these parts due to the hydraulic pressure developed in the rubber bag in pressing the hat. In the operation of this device it is necessary to release the pressure of the bag before the mold and the bag carrying section are separated.

In the hydraulic construction of hat press 1 employ a suitable frame 60 with vertical rods 61 slidably mounted therein, there being a cross head 62 at the bottom of these rods and connecting same together. The tops of the rods have a substantial beam 63 with a depending neck 64 to which is connected the bag holding structure 65, this having a dome 66, and the bag being secured to the dome in much the same manner as in the preceding figures.

The lower part of the machine has a carrier plate 67 with side walls 68 extending thereabove. These side walls have openings 69 to afford circulation of air to supply the gas burners. Brackets 70 extend laterally from the side plates and are slidable on the rods 61. The plate 67 and the side walls support the mold much in the same manner as illustrated in the prior figures, the mold having an annular flange or rim resting on the walls 68. The manner of shifting the upper and lower moving parts of the press utilizes a pair of hydraulic cylinders 71 which are supported in a substantial frame 72 attached to the frame 60. Each of these cylinders has an upper piston 73 and a lower piston 74. Each piston has a piston rod 75. The rods of the upper pistons are secured to the base plate 67 carrying the mold, and the piston rods of the lower pistons are connected to the cross heads 62. Therefore, when the hydraulic fluid operates in the cylinders it forces the pistons apart to bring the mold and the section carrying the bag together, which action raises the mold and pulls down on the upper unit carrying the bag. In the reverse action for opening the press for inserting and removing the hat, the pistons are drawn together, thus lowering the mold and raising the upper part carrying the expandible bag.

It is necessary and desirable first to clamp the mold and the upper section having the bag firmly together prior to the hat pressing operation and this is done by the following mechanism.

The clamp designated generally at 80 has a pair of segments 81, these being hinged together by a hinge pin 82, such pin being on the outside of one of the rods 61 and the segments curving around the rod on each side. Each segment at the opposite side has an outwardly extending arm 83, which arms support piston rods 84 (note particularly Figs. 10, 11, 12, and 13). Such piston rods operate through the heads of a pair of connected

cylinders 85 and have the pistons 86 therein, such cylinders being connected end to end by a connecting plate 87. Springs 88 are positioned between the arms and the ends of the cylinders, such springs tending to force the pistons outwardly and thus open up the clamp. When the cylinders are moved in by hydraulic pressure as detailed below the clamp is tightened and maintained in its tightened clamped position.

10 The general hydraulic power mechanism for operating the main cylinders 71 and also the clamp utilizes a hydraulic compressor or pump 89, this drawing from a supply tank 90, there being a pipe 91 from the tank to the pump and a pipe 92 from the pump to a control valve 93, and from the control valve there is a pipe 94 back to the tank. Branching from the control valve there is a lead 95 with branches 96 and 97 leading to the center of the cylinders 71. Another lead 20 98 has branches 99 and 100 to the outer ends of the cylinders. There is a bypass 101 having check valves 102 and 103 short circuiting the control valve.

25 The control valve illustrated particularly in Figs. 14 and 15 is provided with a valve casing 104 with ports connecting the leads 92, 94, 95, and 98 and has a plurality of connections as 105, 106, and 107. The valve housing has a branch 108 from the supply pipe 92. In the operation of this control valve when in the position of Fig. 15 30 the flow from the pump is led to the center of the hydraulic cylinders and forces the pistons outwardly, maintaining them in this position, and as the pump is continually operated when the desired pressure is reached, the oil is bypassed by the bypass 101 to the storage tank 90. When the oil is flowing into the center of these cylinders through the pipe 95 it is flowing out of the ends through the pipe 98 and back by the connection 40 107 to the storage tank, the inflow being through the connection 95. When the oil is being forced to the outer end of the cylinders as in Fig. 14 the force flow is through the connection 105 from the lead 92 to 98 and the return is from the lead 95, the connection 106, and the lead 94 to the oil tank.

45 In controlling the clamping cylinders, the pump has a supply line 109, a controlling valve 110, and return line 111, and a line 112 from the storage tank 113. The valve has a lead 113' to branches 114 and 115, these branches connecting to the ends of the clamping cylinders outside of the pistons. A bypass 116 is arranged having a check valve 117 therein.

50 In this hydraulic clamping the valve 110 may be operated to stop the flow through the pipe 111 and divert it from the pipes 109 to 114 and 115 and hence force the pistons inwardly against the compression of the springs 88. This action draws 55 in on the clamping segments and clamps the dome and the mold assembly. When the desired pressure has been reached in these clamping cylinders the check valve 117 allows the excess oil to flow through the bypass 116 back to the pipe 60 111 and thence to the oil tank.

65 It is obvious that may other different arrangements of valves and hydraulic pipe connections can be used, the essential characteristics being that when the mold assembly and the dome with the bag are brought into contact the clamp may be operated to clamp these elements together and hold them in this clamped position when the press is in operation and then to release the clamp, the spring forcing the pistons outwardly and thus 70 returning the hydraulic fluid to the storage tank.

An important characteristic of my invention from the standpoint of practicability and utility is that the mold section having the mold block and the dome carrying the bag holding structure can be made comparatively light and substantially counterbalanced. These when in a position for pressing and blocking a hat can have the clamps operated to engage the flanges or margins of the mold member and the dome member but this clamp does not need to be of such character as to 10 press these two parts together tightly. The flanges or marginal edges of the dome or the mold are brought into tight fitting relation with the clamps when pressure is developed in the rubber bag which causes a slight expansion or separation of the mold member and the dome member. Therefore, the greater the pressure in pressing or blocking a hat the tighter is the clamping action, hence the parts do not need to be made heavy to withstand an internal pressure except 15 such as is sufficient to hold the pressure but not sufficient to hold the elements in their position for pressing.

20 Another important characteristic of the invention is that the supply pump for developing the hydraulic pressure in the bag is carried by the dome member. Therefore, this pump is always in a position to be operated to increase the pressure in the bag and does not require a flexible hose connection from a hydraulic pressure source 25 to the expansible bag. In practice a water vessel or reservoir is carried by the dome and directly connected to the feed pipe 54. Therefore, the water supply is also carried directly by the dome.

30 Various changes may be made in the details of construction without departing from the spirit or scope of the invention as defined by the appended claims.

35 I claim:

1. A mold having in combination a stand with 40 a pair of vertical rods slidably mounted therein, a dome having an expansible bag connected to the upper ends of the rods, a bottom plate supporting a mold with means to heat the mold, the said bottom plate being guided on the rods, an interconnecting means mounted in the stand and having an operative connection with the said rods and the bottom plate to reciprocate the rods with the dome and the bottom plate with the mold simultaneously in opposite directions, 45 means to clamp the dome with the bag when in contact with the mold, and a pump means on the dome to expand the said bag independently of the reciprocating means.

2. A press having in combination a stand, a pair of guide rods slidably mounted therein and having a lower and an upper cross head connecting the rods, a dome connected to the upper cross head and having an expansible bag depending therefrom, a bottom plate having a mold 55 mounted thereon, the said bottom plate being guided on the rods, a lifting and lowering means mounted in the stand and having an operative connection to the lower cross head and to the said bottom plate to simultaneously reciprocate 60 the bottom plate with the mold and the dome with the bag in opposite directions, means to clamp the dome and the mold when in engagement, and a pump means on the dome to expand the bag independently of the reciprocating 65 means.

3. A press having a mold, a structure having an expansible bag to fit in the mold, means to simultaneously move both the mold and the structure having the bag toward and from each other, a 70

clamping means engaging the said structure and the mold to secure same together, and means to inflate the said bag operative independently of said moving means and subsequent to contacting of the mold and the said structure.

4. A press having a mold, a structure having a marginal rim with an expansible bag to fit in the mold, means to simultaneously move both the mold and the structure having the bag toward and from each other, a clamping means engaging the rim of the said structure and the mold to hold same in engagement, and means to inflate the bag operative independently of said moving means and subsequent to contacting and clamping of the mold and the said structure.

5. A press having a mold with a peripheral flange or rim, a dome structure having a peripheral rim, an expansible bag secured to the dome structure to fit in the mold, means to simultaneously move both the mold and the dome with the bag toward and from each other, a clamp engaging the rims of the dome and the mold to hold same in engagement, and means to inflate the bag operative independently of said moving means and subsequent to contacting and clamping of the mold and the said structure.

6. A press having a guide structure with a mold and a dome having an expansible bag superposed above the mold, means to simultaneously move the mold and the said dome with the bag in a vertical direction toward and from each other to insert the bag in the mold, the said dome and mold each having a peripheral rim or flange, a clamp having segments engaging the said rims, and means to secure said clamp to retain the said dome and mold in a contiguous position, and means to inflate the bag operative independently of said moving means and subsequent to clamping of the mold and dome.

7. A press having a guide structure, a mold, a dome having an expansible bag mounted for vertical reciprocation with the dome superposed, means to simultaneously move both the mold and the dome toward and from each other, a clamping means carried by the dome and engaging the mold to clamp the dome and the mold together, and a pump on the dome to inflate the bag operative independently of the moving means and subsequent to clamping of the dome and the mold.

8. A press as claimed in claim 7, the dome and the mold each having a peripheral rim or flange, and the clamp comprising segments following the contour of the said rims or flanges, the said segments having upper and lower flanges to engage the upper surface of the flange on the dome and the lower surface of the flange on the mold, the bag when inflated causing a tight fit of the flanges and the clamp.

9. A press having in combination a stand with a guide means connected thereto, a mold, a dome having an expansible bag mounted in said guide means with the dome superposed, a hydraulic cylinder, a connection from the cylinder to the mold and to the dome to simultaneously move the mold and the dome toward and from each other, a pump on the dome to inflate the bag operative independently of said moving connection and subsequent to contacting of the mold and dome, and a clamping means to engage the mold and the dome and to retain same in a contiguous position.

10. A press comprising in combination a stand, a pair of lifting and guide rods slidably mounted therein, a lower and upper crosshead connecting

the rods, a mold slidably mounted on said rods, a dome having an expansible bag connected to the upper crosshead, a hydraulic cylinder mounted in the stand and having pistons therein with piston rods connecting to the mold and the lower crosshead, means to control a flow of hydraulic fluid to and from the cylinder to simultaneously move the mold and the dome toward and from each other, and a pump on the dome to inflate the bag.

11. A press comprising in combination a stand having guide rods with lower and upper crossheads connecting said rods, the rods being vertically movable in the stand, a mold slidably mounted on the rods, a dome having an expansible bag connected to the upper crosshead, a rock shaft mounted in the stand, a lever and link connection between said rock shaft and the mold and the lower crosshead, means to rock said shaft to simultaneously move the mold and the dome toward and from each other, and means to inflate the bag, said mold and dome being substantially counterbalanced on the rock shaft.

12. A press having a stand, a pair of vertical rods slidably mounted in the stand, a pressure structure connected to the upper ends of the rods, a crosshead connected to the lower ends of the rods, a mold slidably mounted on the rods, an operating means interconnected between the mold and the crosshead whereby the pressure structure and the mold substantially balance each other, and a common control device for said operating means to simultaneously lower the pressure structure with the rods and to simultaneously raise the mold to bring these into contact and into pressure relation, and by an opposite simultaneous movement separate the pressure structure and the mold, the pressure structure and the mold having laterally projecting flanges, and a removable clamp having means to engage and release said flanges, and means operative after contact of the pressure structure and the mold to exert a hydraulic pressure therebetween.

13. A press having a stand, a pair of vertically slidable rods in the stand having a pressure structure connected to their upper ends, a mold structure slidably mounted on said rods, a rock shaft, a lever and link connection between the rock shaft and the mold structure and between said rock shaft and said rods, said connections causing the pressure structure and the mold to substantially counterbalance each other, and an operating device to actuate said rock shaft to simultaneously raise the mold and to lower the pressure structure to bring these into engagement, or vice versa to simultaneously lower the mold and raise the pressure structure for separation, the clamping ring having a plurality of arms connected together by a hinge, said arms being carried by a flange on the pressure structure, and the mold structure having a flange to be engaged by the arms of the clamp, and means to forcibly tighten said arms around the flanges to clamp the pressure structure and the mold structure together.

14. A press having a stand, a pair of slidable rods, a pressure structure connected to the upper ends of said rods, a crosshead to the lower ends, a mold structure slidably mounted on the rods, a pressure cylinder having pistons therein, one piston being connected to the mold structure and the other to the lower crosshead, said connections permitting substantial balancing of the pressure structure and the mold structure, and means to actuate said cylinders and pistons to

simultaneously raise the mold and lower the pressure structure, or vice versa to lower the mold and to raise the pressure structure.

15. A press as claimed in claim 14, a clamp having a plurality of arms, the pressure structure of the mold having flanges, said arms encircling the flanges, and a hydraulic means having a cylinder and piston to bring the arms into clamping relation with said flanges.

10 16. A press having a stand, an upper pressure structure slidably mounted in relation to the stand, a lower mold structure also slidably mounted in relation to the stand, each of said structures having a lateral flange, means to simultaneously raise the mold and lower the pressure structure to bring these together, a clamp having a plurality of pairs of arms pivotally connected together and carried by the flange on the pressure structure, the arms engaging the flange 15 on the mold structure, and means to tighten said arms into clamping relation with the flanges, said clamping arms and the flanges being a means for holding the pressure structure and mold in pressure relation during the pressing operation.

20 17. A press comprising, in combination, a mold, a dome having an expandable bag, a moving means for simultaneously moving the mold and the dome toward and from each other, said moving means being adapted to substantially counterbalance the mold and the dome, a clamping means carried by the dome and engaging the mold to clamp the mold and dome together when in engagement and to hold these in clamped relation independent of the moving means, and 25 means operative subsequent to the mold and dome engaging and being clamped to inflate the bag.

30 18. A press comprising, in combination, a frame structure having a guide, a mold, a dome having an expandable bag mounted for vertical reciprocation in the guide with the dome superposed, a moving means for simultaneously moving the mold and the dome toward and from each other, a clamping means carried by the dome and engaging the mold to clamp the dome and the mold together when in engagement, a pump on the dome to inflate the bag operative subsequent to the mold and dome engaging and being clamped, said clamping means being adapted to hold the dome and the mold when under

pressure independent of the frame structure or the moving means.

19. A press having a frame with a guide structure, a lower mold, an upper dome having an expandable bag mounted in the guide structure, a moving means for simultaneously moving the mold and the dome with the bag in a vertical direction toward and from each other to insert the bag in the mold, the dome and the mold each having a peripheral rim or flange, a clamp having segments engaging said rims, means to secure the clamp to secure said mold and dome in contiguous position prior to exerting of pressure, a pump on the dome to inflate the bag operative subsequent to the mold and dome engaging and being clamped, said clamps holding the mold and the dome in operative position independently of the moving means and the frame structure, said moving means being adapted to substantially counterbalance the mold and the dome.

20 25 20. A press having a mold, a dome having an expandable bag to fit in the mold, means to simultaneously move the dome and the mold towards each other to bring the same into contact, the said moving means being adapted to simultaneously separate the dome and the mold, means to inflate the bag after contacting of the dome and the mold and independently of the said moving means.

21. A press as claimed in claim 20, means for 30 interconnecting and clamping the mold and the dome when in contact, the said clamping means transmitting tension stresses between the mold and the dome when the said bag is inflated.

35 22. A press having a mold with a peripheral flange, a dome having a peripheral rim, an expandable bag secured to the dome to fit in the mold, means to move the mold and the dome towards each other to bring same in contact, the said moving means being adapted to simultaneously separate the mold and the dome, a clamp loosely engaging the flange and the rim when in contact, and a pump on the dome to inflate the bag operative subsequently to the contacting and clamping of the dome and the 40 mold and operative independently of the said moving means.

45 MORRIS A. SCHWARTZ.
